UNITED STATES PATENT OFFICE.

JESSE A. DUBBS, OF PITTSBURG, PENNSYLVANIA.

DISTILLING OIL.

SPECIFICATION forming part of Letters Patent No. 694,622, dated March 4, 1902.

Application filed March 13, 1901. Serial No. 50,911. (No specimens.)

To all whom it may concern:

Be it known that I, JESSE A. DUBBS, a citizen of the United States, residing at Pittsburgh, in the county of Allegheny and State of Pennsylvania, have invented or discovered certain new and useful Improvements in Distilling Oil, of which improvements the following is a specification.

As stated in an application filed February 28, 1901, Serial No. 49,268, considerable difficulty is found in distilling certain oils—such, for example, as the petroleums found in California, Texas, and in foreign countries—in producing such a molecular change as will permit of the removal of sufficient hydrogen to render the distillate fit for use as an illuminant, &c. When the distillate contains an excess of hydrogen, the heat generated in the combustion of the distillate is not high enough to render the carbon sufficiently incandescent to avoid the production of smoke and offensive odors. I have found that if distillation be effected at a temperature above that required for the vaporization of oil and in the presence of oxygen such a molecular change will be produced that the flame from the combustion of the distillate so produced will be smokeless and free from offensive odors.

The invention is hereinafter more fully described and claimed.

In the accompanying drawings, forming a part of this specification, Figure 1 is a sectional elevation of a still adapted to the practice of my invention, and Fig. 2 is a similar view of a construction applicable to the practice of a modification.

In the practice of my invention the oil is charged into a still 1 of any suitable form or construction and provided with a valve 7, adapted to control the flow of gases from the still. The location of the valve, whether in the gooseneck 8 or elsewhere along the line of flow of the gases, &c., from the still, is immaterial. The oil is then heated by any suitable means known in the art—as, for example, by means of the furnace 2. As soon as vaporization occurs, air, preferably heated, is forced through the oil in such regulated quantities as specified in Letters Patent No. 646,639, granted to me April 3, 1900, in order to avoid the formation of an explosive mixture in the still. As is well known, a liquid

will remain at its vaporizing temperature if the vapor is allowed to escape freely. In order that the oil and vapor may be subjected to a temperature higher than that required for its vaporization, I provide for the maintenance of such a pressure within the still as will require a heat considerably in excess of that usually employed in distilling oil. Such a temperature can be obtained by maintaining a pressure of about five pounds or higher above the pressure in the still under present conditions of practice. This pressure and consequent temperature will vary with the character of the oil from different fields. As the temperature of vaporization increases as the lighter distillates are driven off it will be understood that in the practice of my invention the pressure in the still will be increased, so that at all times the oil and vapor will be subjected to a temperature higher than the vaporizing temperature of the oil at any period of its distillation. The pressure in the still can be regulated by adjusting the valve 7 while the pressure of air being forced into the still is maintained constant, or the air-pressure may be increased without changing the position of the valve 7, or both valve and pressure may be adjusted, as required. The air is introduced through a pipe 3 having perforations within the still. The air may be heated previous to its being discharged into the still by arranging the pipe 3 so that it will be subjected to the heat of the furnace 2, or a coil may be formed in the still so that the air will be heated by the oil previous to its discharge into the oil, as shown and described in the Letters Patent referred to.

In lieu of attaining the desired heat by effecting distillation under pressure the gases, &c., as they come from the still may be passed through a superheating-coil 9, in which the gases, &c., will be subjected to the heat necessary to effect the desired molecular change. When using the superheater, as shown in Fig. 2, distillation is effected, as described in the Letters Patent referred to—i. e., the oil is heated to normal vaporizing temperature and air, either cold or heated, is forced through the oil after vaporization has begun. When using the superheater, either a volume of air in excess of that required for the molecular change effected in the still may be forced into

the latter and pass with the vapor into the superheater or an additional quantity of air, either cold or heated, may be forced into the vapor through the pipe 10 as the vapor enters 5 the superheater.

I claim herein as my invention—

1. As an improvement in the art of distilling oil, the method herein described, which consists in effecting vaporization of the oil by 10 the combined action of heat and air forced through the oil, and in subjecting the vapor to a temperature higher than the vaporizing temperature of the oil, substantially as set forth.

15 2. As an improvement in the art of distil-

ling oil, the method herein described, which consists in effecting a vaporization of the oil by the combined action of heat and air forced through the oil, and controlling the flow of air so as to maintain a pressure in the still 20 substantially higher than atmospheric pressure, whereby the oil and vapor are subjected to a temperature higher than the vaporizing temperature of oil, substantially as set forth.

In testimony whereof I have hereunto set 25 my hand.

JESSE A. DUBBS.
